CLINKER TONGS

Joseph R. Mecuda, Milwaukee, Wis.

Application May 7, 1934, Serial No. 724,266

5 Claims. (Cl. 294—11)

This invention relates to clinker tongs, and more particularly to a clinker tongs adapted for use in connection with large firing equipment.

An object of the invention is to provide a novel 5 clinker tongs adapted for the efficient removal of clinkers of various sizes not conveniently extractable with devices of the type now in use.

A further object of the invention is to provide 10 in a device of the type, a releasable lock for the jaws thereof, in varying juxtaposition.

Other and further objects of the invention will appear as the description proceeds, reference being had to the accompanying drawing, in which:—

15 Fig. 1 is a fragmentary plan view in perspective of a clinker tongs embodying my invention.
Fig. 2 is a side view in elevation of the device.
Fig. 3 is a detail view in elevation of the lock.
Referring more particularly to the drawing, the 20 numeral 10 represents a tubular member forming the body of the device. At the upper end of the tube is a circular flange 11, forming a part of a locking device to be later described. A jaw, 25 12, of multiple arcuate form, is fixed to the lower end of the tubular member 10, and is bent at the point of attachment to form an obtuse angle in the relation of its body with the tubular member 10.

The arcs, 13, in the jaw 12, are graduated progressively larger from the point of the jaw to its 30 attached end. A rod, 14, is journalled within the tube 10, and terminates in an integral jaw 15, which latter has a structure opposing and complementary to that of the jaw 12. The jaw 15 is bent to form an obtuse angle with rod 14, to conform 35 exactly with the angular relationship of jaw 12 and tubular member 10.

The flange 11 is perforated as at 16, to act as a keeper for the bolt 17, supported in housing 18 40 attached to the rod handle 19. A coil expansion spring 20 impels the bolt 17 normally downwardly. The bolt handle 21 is provided for manual withdrawal of the bolt 17.

In operation, the bolt 17 is withdrawn to permit 45 opening of the jaws 12 and 15. A clinker may be grasped between the arcs 13 of the proper size, and after the jaws are turned tight, the bolt 17 may be released whereupon it will lock in one of the perforations 16. The tool may then be withdrawn with the clinker securely locked therein.

Having thus described my invention, what I 50 claim and desire to secure by Letters Patent of the United States, is:—

1. A clinker tongs comprising a tubular portion and a rod member turnable therein, an extension of said rod member bent to form a handle, an opposite extension of said rod member forming a jaw member having a plurality of joined inwardly convex arcs progressively varying in size, and a complementary jaw member formed on the end of said tubular portion for cooperation with said rod jaw member.

2. A clinker tongs comprising a tubular portion and a rod member turnable therein, an extension of said rod member bent to form a handle, an opposite oblique extension of said rod member forming a jaw member having a plurality of joined inwardly convex arcs progressively varying in size, and a complementary jaw member formed on the end of said tubular portion for cooperation with said rod jaw member.

3. A clinker tongs comprising a tubular portion and a rod member turnable therein, an extension of said rod member bent to form a circular handle, an opposite extension of said rod member disposed at an angle thereto forming a jaw member having a plurality of joined inwardly convex arcs progressively varying in size, and a complementary jaw member formed on the end of the said tubular portion for cooperation with said rod jaw member.

4. A clinker tongs comprising a tubular portion and a rod member turnable therein, an extension of said rod member bent to form a circular handle, an opposite oblique extension of said rod member forming a jaw member having a plurality of joined inwardly convex arcs progressively reduced in size, and a complementary jaw member formed on the end of said tubular portion for cooperation with said rod jaw member.

5. In combination, a tubular member, a rod member turnable therein, an extension of said rod member bent to form a circular handle, an opposite oblique extension of said rod member forming a jaw member having a plurality of joined inwardly convex arcs progressively reduced in size, and a complementary jaw member formed on the end of said tubular portion for cooperation with said rod jaw member, a lock housing on said rod member adjacent the handle, a bolt therein, spring means for said bolt, and a circular flange on said tubular member having spaced perforations adapted to receive the bolt.

JOSEPH R. MECUDA.
